UNITED STATES PATENT OFFICE.

JAMES A. PLOPPER, OF CHICAGO, ILLINOIS, ASSIGNOR TO THE PLANO MANUFACTURING COMPANY, OF SAME PLACE.

DESIGN FOR A CHAIN-LINK.

SPECIFICATION forming part of Design No. 34,834, dated July 23, 1901.

Application filed June 8, 1901. Serial No. 63,815. Term of patent 14 years.

To all whom it may concern:

Be it known that I, JAMES A. PLOPPER, a citizen of the United States, residing at Chicago, in the county of Cook and State of Illinois, have invented and produced a new and useful Design for a Chain-Link, of which the following is a specification, reference being had to the accompanying drawings, showing a complete link.

10 Figure 1 is a side elevation of a link made in accordance with my design. Fig. 2 is a plan view of the same. Fig. 3 is a longitudinal central section thereof on the line A A of Fig. 2, and Fig. 4 is an inverted plan view.

15 As shown in the drawings, the leading or material feature of my design is the substantially rectangular link-body having the elongated spur with the convex surface toward the interior of the link projecting upwardly

20 from the hook end thereof. The link-body is composed of the side bars *a*, connected at one end by the cylindrical bearing *b* and at

the other end by the bearing-hook *c*. The side bars *a* are provided at the cylindrical bearing end with the projections *d*, which co-operate with the projections *e* on the other end of the adjacent link to prevent their swinging from alinement except in one direction. The spur *f* is formed upon the hook *c* and has its inner side convex, as shown at *g*, 25 and is concaved on the outer side, as at *h*, and has its upper end rounded, as shown at *j*.

Having thus described my invention, what I claim as new, and desire to secure by Letters Patent, is—

25 The design for a chain-link, substantially as herein shown and described.

In testimony whereof I have signed my name to this specification in the presence of two subscribing witnesses.

30 JAMES A. PLOPPER.
